UNITED STATES PATENT OFFICE.

JAMES HANCHETT AND JOSEPH R. GILL, OF CHARLESTON, ILLINOIS.

IMPROVED WASHING-MACHINE.

Specification forming part of Letters Patent No. **40,688**, dated November 24, 1863.

To all whom it may concern:

Be it known that we, JAMES HANCHETT and JOSEPH R. GILL, both of Charleston, in the county of Cole and State of Illinois, have invented a new and Improved Clothes-Washing Machine; and we do hereby declare that the following is a full, clear, and exact description of the same, reference being had to the accompanying drawings, making a part of this specification, in which—

Figure 1 is a side sectional view of our invention, taken in the line *x x*, Fig. 2; Fig. 2, a plan or top view of the same; Fig. 3, a transverse vertical section of the same, taken in the line *y y*, Fig. 1; Fig. 4, a section of the same, taken in the line *z z*, Fig. 1.

Similar letters of reference indicate corresponding parts in the several figures.

To enable those skilled in the art to fully understand and construct our invention, we will proceed to describe it.

A is the suds-box, the bottom *a* of which is of curved form, as shown in Fig. 1. The suds-box has a set-off, *B*, at one end, in which a wash-board, *C*, is placed. This wash-board is constructed similarly to the ordinary hand wash-boards, one side being fluted and the other side being smooth, and it has notches *b b* in its lower end at each side, which rest on pins *c* at the sides of the suds-box. This wash-board, when used as such, rests on the end of the suds-box, as shown in red in Fig. 1, and when not thus used it rests on pins *d* at the sides of the suds-box, and serves as a cover or slop-board for the washing apparatus, as shown in tint in Fig. 1, and prevents the suds from splashing or flying out of the suds-box.

D represents a swinging pressure-board or plunger, which is composed of a fluted board, *e*, and a valve, *f*, the former being attached to two arms, *g g*, the upper ends of which are suspended by pivots *h h* in the upper ends of the supports *E* of the suds-box. The valve *f* is connected to the part *e* by joints or hinges *i*, as shown in Figs. 1 and 2. At the upper parts of the arms *g g* of the pressure-board or plunger there is secured a soap-box, *F*, which also serves, in connection with the wash-board *C*, to cover the washing apparatus and prevent the suds from splashing out of the suds-box.

The washing apparatus is composed of the pressure-board or plunger *D* and a stationary

pressure-board, *G*, the latter having a vertical position and fluted obliquely, as shown in Fig. 3, the flutes from each side of its center being inclined outward from their upper ends downward. This board *G* is directly in front of the plunger *D*, and by having it fluted, as described, the clothes when pressed against it by the action of the plunger *D* are prevented from sliding up against the sides of the suds-box and being compressed into wads, a contingency of frequent occurrence in washing-machines of this class. By our arrangement the clothes have a tendency to pass toward the center of the board *G* as they are pressed against it.

The pressure-board or plunger *D* is operated as follows: An arm, *H*, is attached to the lower parts of the arms *g g* of the plunger *D* by a shaft, *j*, the journals of which are fitted loosely in said arms, and to the outer end of the arm, *H*, a bent or curved metallic bar, *I*, is attached by a hinge or joint, *k*. This bent bar, *I*, passes over the back end of the suds-box *A*, and is attached to a shaft, *J*, which has its bearings, *K K'*, secured on the sides of a slop-box, *L*, attached to the back end of the suds-box *A*.

To the curved or bent bar *I*, at its elevated part, there is attached at right angles a bar, *M*, which projects beyond the side of the suds-box and is connected by a link, *N*, with a lever, *O*, which is fitted on a pin, *l*, at one side of the suds-box. By this arrangement a sufficient length of swing may be given the plunger *D*, with a moderate length of movement of the lever *O*, and children may operate the machine equally as well as a grown person, the lever *O* being curved downward at its free or disengaged end so that it may be conveniently grasped by children. The weight of the bent bar *I* materially aids in operating the plunger, as it assists the lever *O* both in its upward and downward movement, and it admits of a deep suds-box being used, and a direct action at the same time being obtained on the plunger without complicated connecting rods or bars. The length of the stroke or swing of the plunger *D* may be varied by connecting the link *N* to the lever *O* at different points, several holes being made in *O* for that purpose. The lever *O* is secured on the pin *l* by having a groove, *m*, made in it, in which groove a pin, *u*, which passes through the lever *O* fits. (See Fig. 4.) By this arrange-

ment the lever O is allowed to work freely on the pin and at the same time the former is secured firmly to the latter. By having the set-off B at one end of the suds-box A, a space is allowed underneath to place a clothes receptacle of any kind, and a wringer may be attached to the outer end of a set off and clothes passed from the suds-box through the wringer and into the receptacle with the greatest facility. The back end of the suds-box A is supported by wheels P, the axle Q of which is fitted in the lower parts of two of the supports E E. These wheels admit of the machine being readily moved or transported from place to place, and are a great convenience. The bearings K K' of the shaft J are attached, one of them, K, permanently to the slop-box L, and the other, K', is attached by a pin or screw, n', which passes through one end of it. These bearings have each a series of holes, o, made in them to admit of the plunger D working nearer to or farther from the board G, to suit the quantity of clothes being washed and also the kind or quality of clothes. The journals of the shaft J may be fitted in any of these holes by turning outward the bearing K', which will admit of the shaft J being withdrawn from and inserted in any of the holes. The bearing K' is secured in position by a hook, p, or any other suitable fastening. The slop-box L catches any suds which may be thrown over the back end of the suds-box A. The valve f admits of the plunger D passing readily back from the board G, obviating splashing of water and causing the plunger to work easily or with a moderate expenditure

of power. The bottom a we prefer to have made of sheet-metal, zinc being a good material. We bend the edges of the metal upward at right angles to the main part and fit the bent edges in grooves made in the lower edges of the sides of the suds-box A, and strips g may be nailed over the zinc.

We do not claim a swinging pressure-board or plunger in connection with a stationary one, for they have been previously used; but,

Having thus described our invention, what we claim as new, and desire to secure by Letters Patent, is—

1. The swinging pressure-board or plunger D, provided with a valve, f, in combination with the stationary pressure-board G, provided with oblique or inclined flutes or projections, all arranged as and for the purpose specified.

2. The combination of the arm H, bent or curved bar I, shaft J, bar M, link N, and lever O, arranged substantially as shown, for the purpose of operating the swinging pressure-board or plunger D.

3. The fixed and movable bearings K K', provided each with a series of holes, o, for regulating the operation of the pressure board or plunger D, relatively with the board G, as set forth, when used in combination with a catch, p, and toggle-lever H I, substantially as described.

JAMES HANCHETT.
